UNITED STATES PATENT OFFICE.

DORSETT ALLEN DAVISON, OF RICHMOND, VIRGINIA.

INTERNAL-COMBUSTION ENGINE.

1,271,137.

Specification of Letters Patent. Patented July 2, 1918.

Application filed December 13, 1915. Serial No. 66,491.

To all whom it may concern:

Be it known that I, DORSETT ALLEN DAVISON, a citizen of the United States, residing at Richmond, in the county of Henrico and State of Virginia, have invented certain new and useful Improvements in Internal-Combustion and Steam Engines, of which the following is a specification.

My invention relates to internal combustion and steam engines, and more particularly to the valve mechanism therefor, and it is the nature of an improvement on the engine forming the subject matter of my application filed June 14th, 1915, Serial No. 34017, and that filed February 4th, 1915, Serial No. 6150.

The object of my invention is to provide a rotary valve for the controlling of the admission of gas or vapor to, and also of the outflow of gas from the piston, which valve shall require a small amount of power for its operation, and which valve shall at all times fit its seat with sufficient closeness to prevent undue leakage of gas during the cycles of the engine, and at the same time admit of proper lubrication.

It is also my object to provide a means for mounting the rotary valve whereby I can readily set it for the proper timing of intake, compression and exhaust; and also whereby it may be easily removed for cleaning, and be replaced.

Referring to the drawings which accompany and form a part of this specification, and in which like numerals refer to like parts in the several views:—

Figure I is a view partly in vertical section and partly in elevation of a two cylinder engine embodying my invention. Fig. II is an enlarged detail view showing the rotary valve. Fig. III is an enlarged detail view, in cross section on line *a—a* in Fig. I, showing the rotary valve within the cylinder. Fig. IV is a section on line *b—b* in Fig. III.

Fig. V is a longitudinal section through the head end of a horizontal cylinder showing the valve and a form of driving member differing in detail from that shown in preceding figures; and Fig. VI is a cross section through the valve and cylinder on line *d—d* in Fig. V.

In Fig. I:—1 is an engine cylinder, with cylinder cover 2, both being jacketed as at 3, 3. In the cylinder wall there are provided ports 4 and 5 for the admission and

exhaust, respectively, of the gases or other fluid used in the operation of the engine. In the cylinder head is an aperture 6 for the insertion of the spark plug, the latter not being shown. 7, 7 are openings for the admission of lubricants.

Arranged within the cylinder is a liner 8, the outside diameter of which is less at all points than the adjacent inside diameter of the cylinder. Consequently the liner is free to be revolved within the cylinder.

Within the liner there reciprocates a piston 9, driving through the connecting rod 10 and crank 11 the shaft 12. The liner 8 is caused to revolve preferably by means of gearing. This gearing may be arranged in one or more ways, and in Fig. I I have shown an arrangement of gears, 30 and 24, by which the liner may be suitably and economically revolved. It will be noted that the liner is shown as carried by ball bearings, 13 and 14; the object of these bearings being to reduce friction. In some cases I find it advantageous to use a radial bearing, as at 15, 80 to take side thrust.

16 and 17 are expandable packing rings. These may be arranged as shown here; or both of them may be placed either above or below the lower thrust bearing. It will have been noted above that since the liner may be revolved within the cylinder there must be a space, 18, however small, between the two. This space is occupied by lubricant. The packing rings 16 and 17, prevent this lubricant from escaping too rapidly to the lower part or crank case of the engine. If desired the upper packing ring 16 may be arranged to allow sufficient lubricant to pass to the bearings below. In Fig. V there will be noted a packing ring at 19. This ring may be used in horizontal engines for the purpose of insuring a proper distribution of the lubricant, and to form a flexible support for the end of the liner 8.

It will be noted that the liner 8 forms a rotating surface within which the piston 9 reciprocates. This rotation of the liner adds to the smoothness of the motion of the piston, making wear uniform, improving lubrication and reducing friction.

Also within the cylinder and arranged at the end of the liner is a valve 20, the function of which is to control the inflow of gas to and the outflow of gas from the cylinder 110 of the engine and the piston. This valve 20 is made in the form of an expandible ring;

and it is provided with an opening or port 21, which may be located at any point in its circumference, but preferably at the joint or "split," and which is arranged so that it 5 may be registered with the inlet port of the cylinder for the admission of gas and with the exhaust port for the exhaust of the gas. The registering of the port in the valve with the inlet and exhaust ports of the cylinder is 10 effected by rotating the valve, and this I do by connecting the valve to the end of the liner 8, and in such a manner that it rotates with the liner and is at the same time free to expand against the wall of the cylinder. 15 The fact that the valve is expandible allows it to make a close contact with the cylinder wall without binding. This valve is shown in detail in Figs. II, III and IV.

In the end of the wall of the liner I provide a number of teeth or notches 22 which are adapted to engage like teeth or notches 23, in one edge of the valve 20; the form of the teeth being such that, while they form a comparatively close joint, the valve 20 is 25 free to expand against the cylinder wall. It will now be seen that upon the rotating of the liner 8, the valve 20 will also rotate, its port 21 being brought into registration with the cylinder exhaust and inlet ports successively.

One of the disadvantages of the ordinary type of valve, and particularly that of the puppet type, is that after being in service for any length of time it does not hold 35 tightly against its seat, sometimes because of a bending of the valve stem, or at other times because of a deposit of carbon or of scale upon the contacting surfaces of the valve and seat. When the valve so affected 40 is the exhaust valve of the engine, at the period of compression a portion of the charge is allowed to escape by the exhaust valve, resulting in waste of fuel and loss of power. So also if the inlet valve is affected 45 in this way, a portion of the charge is lost during compression. Similarly, during the firing period a portion of the effect of the charge is lost if one or both of the valves are not properly seated.

50 The inlet and exhaust valves of an internal combustion engine are opened against the action of springs, and the exhaust valve is also opened while the gaseous contents of the cylinder are under compression; consequently the valves are opened against pressure, and in so opening them there is consumed considerable power which would otherwise have been available for useful effort at the shaft of the engine.

55 My rotating form of valve overcomes these disadvantages. In the first place the greater the compression of the gases, or the greater the expansive force of the gases at firing, the closer will the valve contact with 60 the wall of the cylinder to form a gas tight

joint. In the second place, whatever the compression of the gases within the cylinder, the operation of the valve is but little affected, since it rotates in the gases and is not moved against them. The pressure of 70 the valve against the cylinder wall during compression and firing is amply compensated for by the lubrication of the valve. But during compression and firing there would be an opportunity for a small portion 75 of the gases to find an exit between the notches 22 and 23 of the liner and the valve, respectively. The only means of escape for these gases would be by way of the space 18 between the outside wall of the liner and the 80 inside wall of the cylinder. But escape of the gases by this space is effectually prevented by the lubricant with which the space 18 is filled, and by the packing rings 17 and 16. Such oil as may escape will lubricate 85 the lower bearings of the liner, and subsequently the shaft bearings; any surplus thereafter falling to the bottom of the crank case, whence it may be pumped again to lubricate the valve and the liner. Suitable 90 orifices 25 may be provided in the wall of the liner to allow lubricant to pass from the exterior to the interior wall for the purpose of lubricating the piston.

Thus I provide an expandible valve 95 adapted to make a gas tight joint with the walls of the cylinder, which may be rotated by means of a non-expandible rotating member through a flexible or sliding connection, and which requires but a small proportion 100 of the power of the engine to rotate it. At the same time any gas, which under pressure, may escape from the combustion space of the cylinder, is turned to good account in assisting in a forced feed of the lubricant supplied 105 to the working parts of the engine.

I have now described the general arrangement of the parts of my engine and the manner in which the valve is operated. A consideration of importance in the operation of 110 any engine is that of proper timing of the valves; that is, the timing of the opening and closing of the valves, and particularly of the gas inlet valve, in relation to the position of the crank of the engine. In setting 115 my valve for timing, the cylinder head being removed, the valve is merely rotated, independently of the liner, in the desired direction. When it has been rotated sufficiently the teeth in the edge of the valves are allowed to engage the teeth in the edge of the liner.

In the drawings I have generally shown the engine as of the vertical type. My improvements are equally adapted to the horizontal type of engine; Figs. V and VI. I have also illustrated a gearing of the bevel type. Spur gears, or worm gears, or radial gears may also be used, to suit different classes of engines; it being necessary how- 120 125 130

ever to obtain a fixed relation between the number of revolutions per minute of the valve and of the crank.

What I claim, and desire to protect by 5 Letters Patent in the United States, is—

1. In an internal combustion engine of the rotary valve type, the combination with a cylinder having inlet and exhaust ports therein, of a liner rotatable in the cylinder, 10 a piston working in the liner, and an annular expansible ported valve adapted to control the flow of gas through the ports of the cylinder, and connected with the adjacent end of the liner, and adjustable there- 15 with to change the relation between the position of the port in the valve and the position of the piston.
2. In an internal combustion engine of the rotary valve type, the combination with 20 a cylinder having inlet and exhaust ports therein, of a liner rotatable in the cylinder, a piston working in the liner, and an independent resilient annular valve located at one end of the liner and interlocking with 25 the adjacent end of the said liner, said annular valve being provided with a port and being adapted in the operation of the engine to control the flow of gas through the ports in the cylinder.
3. In an internal combustion engine of 30 the rotary valve type, the combination with a cylinder having inlet and exhaust ports therein, of a liner rotatable in the cylinder, a piston working in the liner, and an annular split band located at one end of the liner and interlocking with the adjacent end of the said liner, said annular band being provided with a port and being adapted in 35 the operation of the engine to control the flow of gas through the ports of the cylinder.
4. In an internal combustion engine of 40 the rotary valve type, the combination with a cylinder having inlet and exhaust ports therein, of a liner rotatable in the cylinder, a piston working in the liner, and an annular expansible valve located at one end of 45 the liner and adjustably connected and adapted to rotate with the said liner, the 50 said valve being adapted to control the flow of gas through the ports of the cylinder.
5. The combination of a cylinder having 55 inlet and exhaust ports, cylindrical liner rotatable within the cylinder, a rotary valve adjustably mounted on the liner and adapt- 60 ed to rotate with the liner and to control the ports in the cylinder, and means for rotating the liner.

6. In an internal combustion engine the 65 combination of a cylinder having ports at its head end for admission and outlet of gas, an elastic annular valve making a close contact with the inner wall of the cylinder, and adapted to control the flow of gas through the cylinder ports, a liner rotatable within

the cylinder and of less outside diameter than the inside diameter of the cylinder so as to form an annular space for the reception of lubricant, and having adjacent its crank end one or more packing rings to im- 70 pede the escape of lubricant; the said liner being connected at its head end with the adjacent edge of the valve by means of serrations so arranged that the rotating liner will rotate the valve, and the said serrations so fitting with one another that lubricant may pass through the interstices to the inside surface of the liner, and means for rotating the liner.

7. In an internal combustion engine the 80 combination of a cylinder having ports at its head end for admission and outlet of gas, an elastic annular valve making a close contact with the inner wall of the cylinder, and adapted to control the flow of gas through 85 the cylinder ports, a liner rotatable within the cylinder and of less outside diameter than the inside diameter of the cylinder so as to form an annular space for the reception of lubricant, and having adjacent its 90 crank end one or more packing rings to im- pede the escape of lubricant; the said liner being connected at its head end with the adjacent edge of the valve by means of serrations so arranged that the rotating liner will 95 rotate the valve, and means for rotating the liner.

8. In an internal combustion engine the 100 combination of a cylinder head; a liner rotatable in the cylinder and extending upward therein to a point adjacent but below the inlet and exhaust ports, a piston working in the liner, and an annular expansible ported valve extending between the liner and the cylinder head, and adapted to make 105 close contact with the wall of the cylinder to control the flow of gas through the ports therein, and adjustably connected with the adjacent end of the liner so that the rotat- 110 ing liner will rotate the valve to control the flow of gas through the cylinder ports.

9. In an internal combustion engine of the 115 rotary valve type, the combination with a cylinder having inlet and exhaust ports therein, of a liner rotatable in the cylinder, a piston working in the liner, and an annular expansible ported valve adapted to control the flow of gas through the ports of the cylinder, and connected with the adjacent end of the liner by means of tooth projec- 120 tions, the said projections being so formed that the valve is free to be expanded out- wardly by the compression or explosion of gases within the combustion chamber to form a close contact with the wall of the 125 cylinder to control the ports therein.

10. In an internal combustion engine the 130 combination of a cylinder having adjacent its head end inlet and exhaust ports, a liner rotatable within the cylinder, the outside

diameter of this liner being appreciably less than the inside diameter of the cylinder to form an annular space between the walls of the cylinder and liner for the reception of lubricant, means adjacent the crank end of the liner for controlling the crankward flow of the lubricant in the annular space between the cylinder and the liner, an annular expansible ported valve located within the cylinder between the liner and the cylinder head, adapted to control the flow of gas through the ports in the cylinder wall, and connected with the adjacent end of the liner by means of driving projections, which projections are so arranged that the valve is free to expand under the influence of compressed or expanding gases to form a close contact with the wall of the cylinder.

11. In an internal combustion engine, the combination of a cylinder having inlet and exhaust ports therein, a liner rotatable in the cylinder, a piston working in the liner, an annular split band located at one end of the liner and interlocking with the adjacent end of the liner, said annular band being provided with a port and being adapted in the operation of the engine to control the flow of gas through the ports in the cylinder, and means for injecting lubricant be-

tween the inner wall of the cylinder and the outer surfaces of the liner and the annular split band.

12. In an internal combustion engine, the combination of a cylinder having inlet and exhaust ports therein, an elastic annular valve making close contact with the inner wall of the cylinder and adapted to control the flow of gas through the ports in the cylinder, a liner rotatable within the cylinder and of less outside diameter than the inside diameter of the cylinder so as to form an annular space for the reception of lubricant, and having adjacent its crank end one or more packing rings to impede the escape of lubricant; the said liner being connected at its head end with the adjacent edge of the valve by means of serrations so arranged that the rotating liner will rotate the valve, means for rotating the liner, and means for introducing lubricant between the inner wall of the cylinder and the outer surfaces of the liner and the annular valve.

In testimony whereof I have affixed my signature, in presence of two witnesses.
